Primary Examiner — Elizabeth Albert(74) *Attorney, Agent, or Firm* — Fay Sharpe LLP(57) **CLAIM**

The ornamental design for a clipboard case, as shown and described.

DESCRIPTION

FIG. 1 is top perspective view of a clipboard case showing my new design;

FIG. 2 is a side elevation view thereof;

FIG. 3 is an opposite side elevation view thereof;

FIG. 4 is a front elevation view thereof;

FIG. 5 is a back elevation view thereof;

FIG. 6 is a top plan view thereof; and,

FIG. 7 is a bottom plan view thereof.

The broken lines showing features on the clipboard case are included for the purpose of showing portions that form no part of the claimed design.
